UNITED STATES PATENT OFFICE.

GEORGE J. ZEIS, OF BUFFALO, NEW YORK.

DESIGN FOR AN AUTOMOBILE RADIATOR ORNAMENT.

Application filed February 12, 1927. Serial No. 20,721. Term of patent 3½ years.

To all whom it may concern:

Be it known that I, GEORGE J. ZEIS, a citizen of the United States, residing at Buffalo, in the county of Erie and State of New York, have invented a new, original, and ornamental Design for an Automobile Radiator Ornament, of which the following is a specification, reference being had to the accompanying drawing, forming part thereof.

In these drawings:—

Figure 1 is a side elevation of an auto-

mobile radiator ornament, showing my new design.

Figure 2 is a top plan view of the same.

Figure 3 is a front elevation of the same.

Figures 4 and 5 are cross sections on the correspondingly numbered lines in Fig. 1, and looking in the direction of the arrows associated with these lines.

I claim:—

The ornamental design for an automobile radiator ornament as shown.

GEORGE J. ZEIS.
